UNITED STATES PATENT OFFICE.

THOMAS J. CALLAHAN, OF DAYTON, OHIO.

DUO-GLAZED SASH.

1,211,079.

Specification of Letters Patent.

Patented Jan. 2, 1917.

Application filed October 16, 1914. Serial No. 867,017.

To all whom it may concern:

Be it known that I, THOMAS J. CALLAHAN, a citizen of the United States, residing at Dayton, in the county of Montgomery and 5 State of Ohio, have invented new and useful Improvements in Duo-Glazed Sash, of which the following is a specification.

This invention relates to new and useful improvements in duo-glazed sash.

10 The principal object of my invention is to provide for hot beds and cold frames, a duo-glazed sash in which the glass may be readily and quickly inserted by the user himself. This operation, known as glazing, 15 is brought within the power of the most inexperienced gardener by my removable means for locking or retaining the panes within the sash. These means, to be herein-after described, not only make it possible for 20 the user himself to readily and quickly insert the glass within the sash, but after this operation is completed they will flexibly and firmly hold the panes in their proper positions until removed for cleaning or other 25 purposes. The removal of one or more panes from the top or bottom layer of glass is as simple an operation for the gardener as their initial insertion, and at no time need there be any cause for complaint that the 30 glass cannot be kept clean or broken panes easily replaced.

Other important and incidental objects will be brought out in the following specification and particularly pointed out in the 35 subjoined claim.

In the accompanying drawings, Figure 1 is a perspective view, partly in section, of my improved duo-glazed sash. Fig. 2 is a longitudinal sectional view thereof, looking 40 toward one of the locking strips. And Fig. 3 is a side elevational view, showing my improved duo-glazed sash mounted upon a flower frame.

Throughout the specification and drawings, similar reference characters denote corresponding parts.

In a detailed description of my invention, the numerals 1 and 2 designate the side rails, and 3 and 4 the end rails of my improved 50 sash, said side rails being joined to the end rails in the usual manner. Extending between, and connected to the end rails 3 and 4 are muntins 5 and 6. While I have shown

two of these muntins, any number may be provided depending upon the width of the 55 panes desired, or they may be eliminated altogether and the glass inserted between the side rails themselves. Extending from the upper longitudinal faces of the muntins 5 and 6 are tongues 7, preferably rectangular 60 in cross section and provided for a purpose to be hereinafter explained.

Provided in the inner side face of the side rail 1 is an upper longitudinal groove 8 and a lower longitudinal groove 9. The upper 65 groove 8 is formed to receive glass panes 10 disposed in lapped relation to shed water when the sash is inclined, while the lower groove 9 is adapted to receive panes 11 which are butted together as shown in Fig. 70 2. One side edge of each of the panes 11 is firmly but flexibly held within the groove 9, while the other side edge of each of said panes is likewise supported within a longitudinal groove or opening 12 formed between an extended or flanged portion 13 of the muntin 6 and a strip 14 suitably secured to the bottom face of said muntin. The strip 14 is severed on an angle at the point 75 15 to provide a portion 16 which may be 80 easily attached or detached by screws 17, to permit the ready insertion or removal of one or more of the panes 11.

The side edge of each of the panes 10, opposite that which is received by the groove 85 8, is adapted to rest upon the longitudinal flanged or extended portion 13 of the muntin 6. As before stated, the panes 10 are lapped, that is, each glass pane projects a short distance over the one below it to make 90 a waterproof connection between them. The object of providing these two layers of glass, one disposed a short distance above the other, is to provide a sufficient space between the top and bottom layer for the retention of air, which, when exposed to the sun's rays, will absorb enough heat to prevent the plants below from freezing when the outside temperature is extremely low.

That the glass in the top layer may be as 100 readily inserted and removed as that in the lower, the following means are provided. Adapted to be secured to the end rails 3 and 4 by means of screws 18, are locking members or strips 19 and 20. The strip 19 has 105 formed in its under surface a longitudinal

groove 21 which receives the tongue 7 of the muntin 5, while the strip 20 is provided with a similar groove 22 which receives the tongue 7 of the muntin 6. By means of 5 screws 23 the strips 19 and 20 may be readily attached to and detached from their respective muntins 5 and 6 to hold in place or permit the removal of the panes 10.

As the panes 10 are lapped for the purpose of shedding water, the strips 19 and 20 are peculiarly formed to hold them in such relation when the sash is inclined. Referring to Fig. 1, it will be observed that the under side of each one of the strips 19 and 20 is stepped or serrated to provide a number of shoulders or butting edges 24. These shoulders 24 are located at such points on the strips 19 and 20 that, when the latter are secured to their respective muntins 5 and 6, 15 said shoulders will engage the projecting edges of the lapped panes to firmly lock them to the sash. These locking strips are effective substitutes for the springs, putty and other minor parts which have been used 20 to retain the glass within the sash, and which, because of their tendency to work loose and for other reasons, have proved unsatisfactory in most cases. On the other hand, my improved locking strips are always effective and readily adjusted, to the 25 end that the panes may be easily inserted and removed, and firmly locked in position even though but one corner edge of each pane is engaged by a shoulder 24.

30 The operation of glazing my improved duo-glazed sash may be accomplished by the veriest amateur, and is as follows. The sash is laid bottom side up and the portion 16 of the strip 14 removed. The panes 11 are then fed in to the grooves 9 and 12 through the opening created, the upper edge of the pane first inserted being moved into a groove 25 formed in the end rail 3, while the lower edge of the pane last inserted enters a groove 45 26 formed in the end rail 4, the other upper and lower edges of said panes butting against each other. The portion 16 of the strip 14 is then secured in position by the screws 17, and the sash turned right side up.

50 In describing the operation of glazing the sash I am confining myself to the method of inserting the panes between the side rail 1 and muntin 6, which is similar to that of inserting the glass between the end rail 2 and 55 muntin 5, and between the muntins 5 and 6 or any additional muntins that may be provided. It may be further stated that, for convenience, the lower layer of glass may be completely inserted before the upper face of 60 the sash is glazed.

When the sash has been turned right side up, the locking strip 20 is removed by withdrawing the screws 18 and 23. A pane 10 is then set so that its upper edge will enter a 65 groove 27 formed in the end rail 3, while a

side edge of said pane projects into the groove 8 in the side rail 1. A second pane 10 is then inserted in such a manner that its upper edge will extend beneath the lower edge of the first mentioned pane, and so on until the entire space between the muntin 6 and side rail 1 is filled with panes disposed in lapped relation to each other. When the panes 10 are so lapped, with one side edge of each resting within the groove 8 and the other on the flanged portion 13 of the muntin 6, the strip 20 may be applied to said muntin by the screws 23. Each end of the strip 20, as well as of the strip 19, is also formed in such a manner as to be attachable 70 to the end rails 3 and 4 by the screws 18.

When the strip 20 is secured to the muntin 6 and end rails 3 and 4, the shoulders 24 on said strip will engage the lower left-hand corner edges of the panes 10 to firmly lock them in their lapped positions. The strips 19 and 20 not only lock the lapped panes firmly in position, but insure a sufficiently flexible fastening to permit the glass to contract or expand under varying degrees of 75 temperature without danger of breaking.

It will now be seen that when the sash is placed upon a frame 28, as shown in Fig. 3, the panes of glass in the upper and lower layers will be firmly retained in position at 80 all times.

The method of inserting the glass has already been explained. To remove the panes for cleaning, or to replace those which have become broken, merely requires the removal 100 of the locking strips from the upper layer, or the detachable portions of the retaining strips from the lower layer, whereupon the panes may be readily withdrawn.

The small number of parts used in my improved sash, the ease with which it may be glazed and the firm but flexible way in which the glass is supported, are some of the marked advantages which stand out in favor of its use by the market gardener, florist, amateur or other person or persons engaged in gardening for pleasure or for profit.

I do not wish to be limited to the details of construction and arrangement herein shown and described, and any modifications or alterations may be made therein to suit different conditions of use.

Having described my invention, I claim:

A glazed sash for garden frames, comprising 115 a pair of parallel end members, a pair of side members secured thereto, the inner face of each of said side members having a wide longitudinal groove to receive lapped panes of glass, one or more intermediate longitudinal members, ledges formed on the intermediate member or members to support said glass, a tongue extending upwardly from said intermediate member or members, a grooved strip removably mounted upon said 120 125 130

tongue, and shoulders on the lower longitudinal edge of said strip opposite the ledges, to engage and hold in a lapped position, the panes of glass supported by said longitudinal grooves and ledges, substantially as described.

In testimony whereof I have hereunto set my hand this 14th day of October, 1914.

THOMAS J. CALLAHAN.
